WINDOW SCREENING DEVICE

Werner Dollstedt, Chicago, Ill., and Carl Doll-
stedt, Gary, Ind.

Application September 26, 1938, Serial No. 231,730

3 Claims. (Cl. 156—39)

This invention relates to improvements in window screening devices; and more particularly to such as are operated automatically by the operation of the window sash.

5 One of the main objects of this invention is to provide an improved window screening device which is automatically operated by the opening and closing of the window; and which is readily attachable to the window frame and to the sash, 10 and is likewise easily and quickly detachable therefrom to facilitate cleaning the window sash and sill, and for storing away the device in fall, without operating any screws or securing elements or marring the frame and without the use 15 of any tools.

Another object of this invention is to provide an automatically operating screening device which consists of only a few members that are readily connectable and mountable in position in 20 the window frame, and which are likewise readily removable therefrom, and which preferably consists of a pair of guide members detachably connectable to the window jambs, also an operating mechanism including the screen and which is 25 easily connectable to said guide members and to the window sash, by merely setting the screen equipped mechanism into place between said guide members, and is similarly readily removable therefrom.

30 A further object of this invention is to provide such a screening device which comprises a housing carrying a screen therein and provided with means whereby the outer end of the screen automatically becomes operatively connected to the lower bar of the window sash by the act of 35 mounting the device in place in the window frame, so that the screen will move along with the sash; and in which device the screen has its outer end automatically connected to the housing 40 when the sash is closed, and the housing with the screen can then be readily withdrawn from the window frame and sash when the latter is in its closed position.

Another object of this invention is to provide 45 such a screening device comprising an improved screen roller wherein the parts can be easily put together, to save labor and provide for economy in its manufacture.

These and various other objects and advantages 50 are attained with this invention, as will become apparent from the following description, taken in connection with the accompanying drawings in which this invention is illustrated in its preferred form; it being understood that various 55 other arrangements and forms of construction

may be resorted to for carrying out the objects and purposes of this invention.

In the drawings:

Fig. 1 is a front elevational view showing a closed window having our improved screening device mounted in position thereon.

Fig. 2 is a partial view showing the window slightly open.

Fig. 3 is a side elevational view of the guide member, partly broken away.

Fig. 4 is an enlarged cross-sectional view, taken on line 4—4 of Fig. 1.

Fig. 5 is an enlarged horizontal sectional view, taken on line 5—5 of Fig. 2.

Figs. 6 and 7 are partial perspective views of 15 the pair of readily attachable and detachable side members for guiding the screen.

Fig. 8 is a perspective view of the screening mechanism comprising the casing and the roller and screen therein, being detachably and easily 20 attachable to the side members to secure the device in position.

Figs. 9 and 10 are enlarged vertical sectional views, taken on line 9—9 and 10—10 of Fig. 8.

Fig. 11 is an enlarged vertical sectional view, 25 taken on line 11—11 of Fig. 2.

We have illustrated our invention in the drawings in the preferred form of construction, comprising a pair of side members 11 and 12 which are detachably mounted on the pair of jambs or 30 side members 13 of the window frame; and the screening mechanism 14 which includes a casing or housing 15 carrying therein a roller 16 provided with a screen 17, all combined as a unit. Said housing bears on the lower member or sill 35 18 of the window frame, and the screen 17 is releasably attached to the lower bar 19 of the window sash 19'; so that the mechanism is readily mountable in position between the guide members 11 and 12 and is readily removable therefrom. It is shown installed for screening the lower window opening, and can similarly be applied to the upper opening.

The two side members 11 and 12 are economically constructed from strips of sheet metal 45 formed substantially into the shapes indicated in the drawings, and each member preferably has its parts made into one integral member, to effect economy in construction; altho each may be formed from one strip of metal or from several 50 strips welded together.

The side member 11 comprises an attaching portion or bar 20 adapted to be attached to jamb 13, and has spaced guide plates 21 and 22 extending at an angle therefrom, and for a sub- 55

stantial distance, so as to guide a substantial marginal part of the screen in the included channel or space 23 therebetween, to take care of variations from standard widths of window frames. 5 The lower end of plate 22 is bent inward providing a lip 24 to engage upon housing 15; while a bracket or plate 25 extends from and is integral with the lower end part of member 11, adapted to engage one end of roller 16, and has a lower in- 10 turned end or lip 26 to engage under housing 15, thus holding one end of said housing between the lips 24 and 26 and said bracket 25. Said bracket plate 25 has an aperture 27 therein to receive the round end portion 28 of the rod 29 15 which extends thru the roller 16.

The side member 12, like its companion member 11, comprises an attaching portion or bar 30 to be attached to the opposite jamb 13, and includes spaced guide plates 31 and 32 extending 20 at an angle therefrom, for guiding a substantial marginal part of the screen in the included channel 33 therebetween. The lower end of plate 32 is bent inward providing a lip 34 to engage upon housing 15, and an integral bracket plate 35 extends from the lower end part of member 12, adapted to engage the end of roller 16, and has an inturned lower end providing a lip 36 to engage under the housing 15, thereby holding the end of the housing between said lips 34 and 36 25 and said bracket 35. The bracket 35 has a slanting slot 37 therein to receive the flat end part 38 of the rod 29 of the roller; so that the housing with its roller and screen can be readily installed between the side members by sliding part 38 30 downwardly in slot 37, and thus holding said side members and the mechanism in position and preventing any accidental sliding away or withdrawal of the mechanism.

The bars 20 and 38 of members 11 and 12 have 40 each a notch or opening 40 provided at the upper end and have an aperture or opening 41 near the lower end. A screw or headed element 42 and a pin 43 are secured to each jamb 13, and the members 11 and 12 can then be readily mounted in 45 position by simply tilting the members, as indicated in dot-and-dash lines at the top of Fig. 3, so that notch 40 engages screw 42, and the lower part of the member is pressed to the jamb 13 to bring pin 43 in aperture 41, said side member being thus held by the head of said screw 42. The housing is then slid into position between said side members, thereby securing said 50 members and the screening mechanism in position in the frame, as stated above, and likewise facilitating the quick and easy withdrawal 55 of the entire device in the form of three members or units.

The screening mechanism, which comprises the casing 15 and the roller 16 with the screen 60 17, is arranged to be installed and removed as a unit from the side members 11 and 12 on the window jambs and from the window sash. The housing has a pair of caps 45 on its two ends closing the ends and being adjustably mounted 65 thereon, by means of slots 46 and screws 47, whereby to compensate for slight variations in the widths of the frames; and each cap contains a suitable aperture 48 thru which the end portions 28 and 38 project.

The roller 16 is economically constructed from 70 a strip of sheet metal curved so that its side edges remain slightly spaced and provide a longitudinal slot 50. A pair of heads or head members 51 are pressed into the ends of the roller 75 and a similar member 52 is forced into the in-

termediate portion thereof, each member having a tongue 53 which engages in said slot 50, to hold said member against turning therein. The rod 29 extends thru openings in said members and it has a coil spring 54 thereon having one end secured in the rod and the other end preferably secured in the intermediate member 52, as best shown in Fig. 9. The roller has cleats 55 stamped outward thereon which are hooked to the inner end of screen 17 and are then bent down onto the roller to secure the screen in place thereon, as best shown in Fig. 4; and the screen 17 is thus automatically wound on and operated by the roller in the casing, and is also detachable from the cleats. 15

A reinforcing and attaching member 56 is secured to the outer end of the screen. This member is preferably in the form of a doubled strip of sheet metal including the two portions 57 and 58 with the latter having its lower edge portion 58' turned inward and clamping the bent edge portion of the outer end of screen 17 therebetween. Securing elements 59 may further be used for positively pressing and holding portion 57 against the screen and the bent portion 58', as best shown in Fig. 10, to secure the screen positively therein. Said member 56 is provided with key-slots 61 each having an enlarged lower portion 61' adapted to pass readily over the head 62' of a headed member 62 which is mounted on the sash 19, preferably by securing it to the lower attaching part 63' of a handle 63 fastened on the bar 19 of the sash, by suitable means, as best shown in Fig. 11. Said member 56 is further provided with hooks 65 on its upper end which engage in openings 66 provided in the upper part of casing 15, as best shown in Fig. 8.

With this construction as disclosed above, the side members 11 and 12 can be readily set into place on the window jambs 13, and the mechanism 14 can then be readily placed in position between said members 11 and 12, to mount the entire device in the proper position. The headed members 62 on the window sash and the slots 61 40 on the connecting member 56 are so placed that when the sash is closed the enlarged portions 61' 45 of said slots will be in line with the heads 62' of said member, so as to enable convenient withdrawal of the operating mechanism from the window sash and frame. Whenever the sash is raised said members 62 will engage in the narrow upper parts of slots 61 and will then carry along the attaching member 56 and unroll the screen for screening the window opening; and when the sash is fully closed said heads 62' will again be in line with the enlarged portions 61', as stated above. The hooks 65 engage within openings 66 50 when the window is closed, so as to bring said enlarged portions 61' in line with said heads 62'; but as the sash is raised and members 62 lift the attaching member 56 and the screen, it also lifts the hooks 65 from said openings 66 and from the casing; and will again enter them therein as the window sash is closed. This device can thus be 55 readily removed from the window and frame, by simply lifting said mechanism away from the side members and then sliding said members away from the window frame; and the device likewise can be easily replaced, without the use 60 of any tools, and without removing or operating any screws to mar the window or frame.

We claim:

1. In combination with a window frame and sash having securing elements attached to the 75

- jambs of the frame and headed elements to the end bar of the sash, a screening device comprising a pair of screen guiding members each having an upper and a lower opening to be readily attachable to and detachable from said securing elements on the jambs by tilting and sliding said members, each member including an integral plate with an opening providing a bracket at one end, and a mechanism arranged to be readily mounted as a unit between said brackets to hold the entire device in its operative position and to be readily removed therefrom, said mechanism including a casing having a roller and screen therein provided with an attaching strip secured to its outer end, hooks on said attaching strip which engage in openings on the casing to secure said end thereon when the sash is closed, said strip being provided with keyhole slots which automatically engage said headed elements on the sash by the act of setting the mechanism in position between said brackets, so that the screen is operated but the hooks are released from the casing when the sash is operated, and the strip is automatically released from said headed elements as the mechanism is withdrawn from the brackets. 5
2. In a screening device readily attachable to and detachable from a window frame and its sash containing attaching means on the sash and a headed element and a pin on each jamb of the frame, a screen mechanism and a pair of guide members at its sides, each member consisting of an integral unit including a bar having a notch at one end and an opening adjacent the other end, also a pair of integral flanges extending from the bar providing a channel therebetween for guiding the edge portion of the screen therein, an integral bracket plate extending from one end of each bar and having an opening therein, said mechanism including housing means having a screen roll therein and means at the ends of the roll extending through the housing means to be set into said plate openings, and means on the end of the screen to engage onto the means
- on the sash, whereby the guide members are easily and quickly mounted in position in the frame by simply engaging the notched end onto the headed element and pushing the other end with its opening onto the pin, and then simply setting the mechanism with the screen roll in position between the bracket plates by inserting its end means into the plate openings, thereby securing the guide means and the entire device firmly in place, and at the same time to be readily removable, without the use of any tools or the operating of any securing elements. 10
3. In a screening device readily attachable to and detachable from a window frame and sash containing a pair of headed elements on the sash, also a headed element and a pin on each jamb of the frame, a screen mechanism and a pair of guiding members at the sides thereof, each member consisting of a unit including an attaching bar having a notch at one end and an opening adjacent the other end, whereby each member is readily mounted on the jamb by sliding the notched end onto the headed member and moving the other end onto the pin, a pair of integral flanges extending from the bar providing a channel for guiding the edge portion of the screen therein, an integral bracket plate extending from one end of each bar one having an opening and the other having a slanting slot, the screen mechanism comprising a casing having therein a roller and screen with an attaching strip on its end, holding means on the strip for engaging the casing to hold said end securely thereon when the sash is closed, but to release the casing as the sash is opened, and means on the ends of the mechanism to be moved into the plate opening and slot, said strip being provided with openings for automatically engaging onto the headed elements on the sash by the act of setting the mechanism in position between the bracket plates. 15 20 25 30 35 40
